UNITED STATES PATENT OFFICE.

FRANCISCO PIMENTEL, OF NEW YORK, N. Y.

CODE SYSTEM.

No. 797,016.

Specification of Letters Patent.

Patented Aug. 15, 1905.

Application filed December 8, 1904. Serial No. 236,315.

To all whom it may concern:

Be it known that I, FRANCISCO PIMENTEL, a citizen of the Republic of Venezuela, residing in the city, county, and State of New York, have invented a certain new and useful Code System, of which the following is a specification.

My invention relates to a system of making up messages for transmitting information by cable, telegraph, &c., and has the advantage, among others, of universal applicability to any existing code system, dictionary, or other compendium of terms, meaning by "terms" words, phrases, or numbers, &c.

Moreover, the system has the advantage of economy, since five ordinary code-words can be expressed and transmitted by two of mine, thereby effecting a saving of at least sixty per cent.

Moreover, the system is perfectly simple and easy to understand, apply, and translate and at the same time is capable of absolute secrecy.

I will now proceed to describe the preferred form of my invention and to explain its application.

Starting with any existing code system or with any dictionary or compendium of terms, I divide the listed terms into groups, then apply a suitable biliteral syllable to each of said groups and also biliteral syllables to the

individual members of each group, so that to designate any term in any group and absolutely distinguish it from all the other terms in the list it is only necessary to set down, first, the syllable distinctive of the group to which the term in question belongs, and, secondly, the syllable applied to the term in question in that group. It follows, therefore, that I can designate any word or term by two biliteral syllables, and since under the regulations of the cable tariff it is possible to employ code-words of ten characters it further follows that in my system I can represent by one word of five biliteral syllables two and one-half ordinary code-words or other terms.

Describing now more particularly the syllables which I prefer to employ in making up my code-words, they will consist of various combinations of the letters of the alphabet in pairs. Thus, for example, some two hundred and fifty of these combinations, herein known as "biliteral" syllables, can be formed by taking each one of the vowels and adding to them the various consonants one after the other to form a series of biliteral syllables. I insert herein a list of the various biliteral syllables which may be employed, although in a given code system it may be advisable to use all of these and in other systems it may be advisable to devise and employ still other combinations of letters.

List of Syllables.

(22) aw	(54) el	(86) ia	(118) mi	(150) oy	(182) ul	(214) by	(246) yt
(23) ay	(55) em	(87) ib	(119) ni	(151) oz	(183) um	(215) ey	(247) yv
(24) az	(56) en	(88) ic	(120) pi	(152) bo	(184) un	(216) dy	(248) yw
(25) ba	(57) eo	(89) id	(121) ri	(153) co	(185) uo	(217) fy	(249) yx
(26) ca	(58) ep	(90) ie	(122) si	(154) do	(186) up	(218) gy	(250) yz
(27) da	(59) er	(91) if	(123) ti	(155) fo	(187) ur	(219) hy	
(28) fa	(60) es	(92) ig	(124) vi	(156) go	(188) us	(220) jy	
(29) ga	(61) et	(93) ih	(125) wi	(157) ho	(189) ut	(221) ky	
(30) ha	(62) eu	(94) ij	(126) yi	(158) jo	(190) uu	(222) ly	
(31) ja	(63) ev	(95) ik	(127) zi	(159) ko	(191) uv	(223) my	
(32) ka	(64) ew	(96) il	(128) oa	(160) lo	(192) uw	(224) ny	

Taking the foregoing list, however, as a basis, it will be noted that there are two hundred and fifty of these syllables. I accordingly divide the list of words, for example, in any code system into groups of two hundred and fifty words each. I then apply a different one of the foregoing syllables to each of said groups, which syllable for convenience may be called a "group-syllable." I then apply to each of the two hundred and fifty members of each of the groups one of the said list of syllables, and which may be known as "word" or "term" syllables. Every word, therefore, in a given group has arranged opposite to it a different word-syllable and every group has applied to it a different group-syllable. Consequently to represent any word in any group it is only necessary to set down the group-syllable designating the group to which the word belongs and the word-syllable belonging to the word in question in that group. In this way each of the code-words in a given message may be translated into a bisyllabic combination consisting of a group-syllable and a word-syllable, and assuming that the message contained ten words it would be set down under my system in twenty syllables, ten of which were group-syllables and ten word-syllables, and since the tariff allows the transmission of words of five biliteral syllables I then, starting at the first syllable, count them off in groups of five, thereby forming four words, which means that I am able to transmit in four words ten ordinary code-words or other terms.

It will be evident from the foregoing that I am able by the use of two hundred and fifty biliteral syllables to transmit two hundred and fifty groups of two hundred and fifty terms each—in other words, that I am able to represent and distinguish two hundred and fifty times two hundred and fifty terms—in other words, sixty-two thousand five hundred.

The accompanying drawings illustrate portions of the pages of a code to which my system has been applied.

Figures 1 to 5, inclusive, represent five different sections of the code of two hundred and fifty words each and having, respectively, the group-syllables "to," "la," "ca," "mi," and "no." The remaining Figs. 6, 6^a, 7, and 7^a illustrate my system in its application to a code or compendium of terms in which the words or terms are so numerous as to require division thereof into two or more parts, all as hereinafter more specifically set forth.

The syllables referred to herein as "word" or "term" syllables will be found in the first column of each figure and located opposite the respective code-words to which they belong.

It should be observed that the numbers in the drawings are no part of the system and do not appear in the code as actually used. On the contrary, they are simply reference-numerals corresponding with the numerals

annexed to the syllables in the "list of syllables" given herein. These numerals serve to show that in the actual printed code there are two hundred and fifty word-syllables and two hundred and fifty code-words and expressions under each group-syllable, all of which, however, for brevity's sake have not been shown in the drawings. Thus in Fig. 1 the break between 3 and 24 indicates that all the word-syllables numbered "4" to "23," inclusive, in the list of syllables would be included in the actual code, but are omitted here for the sake of brevity. The same remark applies to all the breaks in sequence in all the figures.

Illustrating now the practical working of my system, suppose it was desired to transmit the message: "There is a change in the market in consequence of small supplies coming to hand. Telegraph cost, freight and insurance, immediate shipment." Upon consulting the code, of which the accompanying drawings show disconnected portions, this message would be represented by the code-words "maundering, congress, supperless, counter, illicitous." Translating now this message in accordance with my system, the first word, "maundering," Fig. 1, has opposite it the word-syllable "na" and belongs to the group of words designated by the group-syllable "to." The word "maundering" is therefore expressed by the two syllables "nato." The next word of the message, "congress, (see Fig. 2,)" is similarly represented by the word-syllable "to" and the group-syllable "la," together forming the expression "tola." Similarly, "supperless," Fig. 3, is represented by "bica," "counter," Fig. 4, by "elmi," and "illicitous," Fig. 5, by "muno." The entire message is therefore represented in my system by the expression "natotolabicaelmi-muno," formed by setting down one after the other the various bisyllabic expressions arrived at above. It will be noted that there are ten biliteral syllables in this expression and that the entire code message, consisting of five code-words, has been represented thereby. Since the code tariff allows the use of words of ten characters, it is only necessary now to count off from the beginning the syllables in groups of five, which gives the two words "natotolabi caelminuno." Thus it will be seen that I have been able to represent the five words in the message by two words, the first two syllables of the expression "natotolabi" identifying "maundering," the next two syllables identifying "congress," and the last or fifth syllable belonging to the word "supperless" and in connection with the first syllable of the next word fully identifying it. Thus one of my words represents two and one-half words of the message.

It will be necessary now to show how my system can be applied to a compendium containing more than sixty-two thousand five hundred terms. For example, suppose we

are dealing with such a compendium in which there are twenty thousand additional words. To apply my invention thereto, I preferably divide the entire work into two parts, part 1 comprising the first sixty-two thousand five hundred terms, and part 2 the remaining twenty thousand. Each part will then be divided into groups with a group-syllable applied thereto, and the terms of said groups will each be designated by designating term-syllables exactly as described heretofore in applying the system to a compendium having only sixty-two thousand five hundred terms. In other words, the system of group and term syllables applied to part 2 will be a mere duplication of those applied to part 1. Thus, to assume our previous example, where the code-words "maundering" and "congress" were represented in my system by the expression "natotola" it will be evident that were the code in question to consist of two parts, the first having sixty-two thousand five hundred words and the second twenty thousand, that the expression "nato" may designate a word in the first part and also a word in the second, and that it will be impossible to tell which of these alternatives exists without additional means, which is the object of the part of my invention which I am now describing, and similarly with the expression "tola." Thus, referring to Figs. 6, 6^a, 7, and 7^a of the drawings, it will be noted that Figs. 6 and 7 belong to the first part of the compendium or code, while Figs. 6^a and 7^a belong to the second part, and that the syllables "na-to" occur both in the first part of the code and in the second (compare Figs. 6 and 6^a) and designate different expressions in the two parts; similarly with the syllables "to-la." (See Figs. 7 and 7^a.) It follows, therefore, that in translating the expression "natotola" there are four possibilities to provide for and distinguish: First, do the expressions "nato" and "tola" designate two words in the first part of the code; second, do they designate two words in the second part; third, does "nato" express a word in the first part and "tola" a word in the second, and, fourth, which is the reverse of three, does "nato" express a word in the second part and "tola" a word in the first? To indicate without mistake which of these four conditions exists, I employ four letters, preferably vowels, each one of which is distinctive of one or the other of the foregoing conditions, and annex said letters to the words formed under my system. Thus, for example, assume the following words:

Natotola-a,
Natotola-e,
Natotola-o,
Natotola-u.

In these expressions the letters "a," "e," "o," "u" are employed to represent the various combinations. Thus the letter "a" designates that "nato" and "tola" both refer to the first part of the compendium; "e," that both refer to the second part; "o," that "nato" refers to the first part and "tola" to the second; and "u" that "nato" refers to the second and "tola" to the first. Of course other letters can be employed for these purposes; but the vowels are to be preferred because they in all cases give pronounceable combinations.

Without enumerating equivalents and without setting forth all the forms which my invention may take, what I claim, and desire to secure by Letters Patent, is—

1. A code system which consists in adopting a series of biliteral syllables; dividing a given compendium of terms into groups, the number of terms in a group being equal to the number of syllables in said series of syllables; designating each group by a different biliteral syllable of said series, hereinafter called a group-syllable; designating each term in a given group by a different biliteral syllable of said series, hereinafter called a term-syllable; representing each term of the message to be transmitted by a group-syllable and a term-syllable; and dividing the series of syllables so obtained to form pentasyllabic words.

2. A code system which consists in adopting a series of biliteral syllables; dividing a given compendium of terms into parts; dividing the terms in each part into groups, embracing the same number of terms as there are syllables in the said adopted series of biliteral syllables; designating each group by a different biliteral syllable of said series, hereinafter called group-syllables; designating each term in a given group by a different biliteral syllable of said series, hereinafter called a term-syllable; representing each term of the message to be transmitted by a group-syllable and a term-syllable; dividing the series of syllables so obtained to form transmission-words; and joining single letters to said transmission-words which signify that said words represent code-words in the same part of the code or in different parts and which furthermore identify said parts.

In testimony whereof I have signed my name to this specification in the presence of two subscribing witnesses.

FRANCISCO PIMENTEL.
